UNITED STATES PATENT OFFICE

HENRY R. HEYL, OF PHILADELPHIA, PENNSYLVANIA.

PAPER CONTAINER.

1,233,356.

Specification of Letters Patent. Patented July 17, 1917.

Application filed June 21, 1916. Serial No. 104,847.

To all whom it may concern:

Be it known that I, HENRY R. HEYL, a citizen of the United States, residing at Philadelphia, in the county of Philadelphia and State of Pennsylvania, have invented 5 certain new and useful Improvements in Paper Containers, of which the following is a specification.

The object of the invention is to provide 10 a paper container commercially efficient as a carrier of liquids, or solids, as a substitute for glass or metal vessels.

The important features of such a container are that it shall be sufficiently strong 15 for the service required of it; thoroughly sterile for a first using; and having a tight lid easily removable and reinsertible many times without destroying the efficiency of the container.

20 The form of the bottom and its rigid attachment to the inside wall of the container is a distinct and important feature of construction; as is also the correct conical shape of the cup adapted to close nesting for convenience and commercial economy in storage and transportation.

These objects are reached in the manner hereinafter set forth, reference being had to the accompanying drawings forming part 30 of this specification, in which—

Figure 1 is a view of a single cup;

Fig. 2 shows in cross section the shape and formation of the cups nested for packing and transportation;

35 Fig. 3 is a top view of a cup or container;

Fig. 4 is a plan view of the flanged lid of the form preferably used;

Fig. 5 is an illustration showing a carton of columns of nested cups and

40 Fig. 6 is a view of a single cup, showing same constructed of three ply material, the plies being designated as α^1 α^2 and α^3 .

Similar letters refer to similar parts throughout the drawings.

45 In order that my invention may be reliably useful as a sanitary, economical container for carrying milk or other food products, I have endeavored to combine in the construction details that are vitally important to high efficiency.

In making a paper container for a single service it is important to use only the least quantity of paper and sterilizing material needed for the purpose of economy, to which 55 matters of commercial necessity I have carefully adhered in working out my invention.

Referring to the drawings α is the body portion of the container. This container must be made from select paper, wound preferably three ply as illustrated in Fig. 60 6 and of such definite taper most suitable for close nesting and for securely holding the lids in place against accidental removal. There must also be provision made against jamming the cups too tightly together; that 65 while fitting snugly within each other they may be always easily separated without the fingers coming in contact with the inside thereof to jeopardize their sterility.

As shown in Figs. 1 and 2 each container 70 has a top c and a two piece bottom g , consisting of a top-flanged piece e and a ring f of thicker material cut from a straight tube placed under the flanged part as a support. The supporting ring f is first inserted with- 75 in the cup and pressed down even with the lower edge thereof; then cement is applied around the top edge of the ring and against the side wall of the cup and the flanged piece is inserted from above and pressed 80 down firmly upon the supporting ring.

Thus my two piece bottom is securely connected to the cup wall against possibility of displacement by the weight of the material in the cup; or by the pressure of the 85 nested cups above it.

Thus I provide a solid column of heavy card board reaching from the lower edge of the bottom cup upward through the entire nest which effectually resists any force to 90 jam the cups tightly together.

There are good reasons for applying a band or hoop b around the top edge of the cup to strengthen it against the outward pressure of the lid and to afford means for 95 firmly holding the cup with the fingers for carrying purposes. This band or collar b around the top of the containers is cut from a straight tube and cemented firmly in place during the process of manufacture. 100

The uniform depth of nesting the cups is controlled by the special form of the two-piece bottom to supply an abutment for each inserted cup to rest upon, regardless of the number so assembled.

105 After the cups are thus completed and allowed to become thoroughly dry they are sterilized in a paraffin bath and immediately nested; each cup becoming a close fitting lid to the one below, while the top one 110 is closed by a flanged lid as shown in Fig. 4.

Four columns of nested cups *h* are inclosed in a sealed wrapper and nine of these packages with their complement of lids *e*, separately boxed, are inclosed in a sealed carton *i*, which makes a practical means for storage and transportation in the most approved form. Such a package only 24" x 24" x 22" contains 500 quart size containers.

10 Having thus described my invention what I claim as new and desire to secure by Letters Patent is:

15 1. A paper container of tapering form adapted to be nested with other containers of like construction, having a two piece bottom consisting of a ring member below to support a flanged member resting upon it, both secured to the inside wall of the container forming a solid column of card board

reaching from the bottom edge of the container body upward to a point where another similar container may rest upon the upper edge of said bottom as a support. 20

2. A paper container made with a body of tapering form adapted to be nested; having a bottom of two members consisting of a flanged top piece resting upon a ring piece of such height that the combined members shall fill the space between the bottom edges of the walls of the nested containers to prevent excessively tight nesting. 25

30 In testimony whereof I affix my signature in presence of two witnesses.

HENRY R. HEYL.
